UNITED STATES PATENT OFFICE.

WILLIAM EWART, OF NIAGARA FALLS, ONTARIO, CANADA.

PIPE.

1,394,292.

Specification of Letters Patent.

Patented Oct. 18, 1921.

Application filed January 10, 1920. Serial No. 350,658.

To all whom it may concern:

Be it known that I, WILLIAM EWART, a subject of the King of Great Britain, residing at Falls View, Niagara Falls, Ontario, 5 Canada, have invented certain new and useful Improvements in Pipes, of which the following is a specification.

This invention relates to smoking appliances, and the primary object of the invention 10 is to provide an improved smoking pipe, so constructed as to prevent the clogging of the bore of the pipe by the tobacco and the wetting of the tobacco by the moisture accumulating in the pipe bore, thereby 15 insuring a clear, sweet, smoke.

A further object of the invention is the provision of a tobacco pipe having an auxiliary stem provided with a plurality of spaced passageways formed on its outer surface 20 which communicate with a longitudinally extending slot bisecting the bore of the supplemental stem. The passageways being so arranged as to preclude the choking thereof by tobacco.

25 A further object of the invention is the provision of an improved smoking pipe having detachably associated therewith a supplemental stem provided with an upwardly and inwardly extending longitudinal slot 30 which communicates with the bore of the pipe, the stem being provided with a plurality of curved passageways for communicating with the slot, the arrangement of the slot in the stem forming a well so as to prevent 35 the moisture accumulating in the stem from coming in contact with the tobacco.

A still further object of the invention is to provide an improved means for holding a supplemental stem in the bore of the pipe 40 against turning movement, so that the slot formed therein will be held in correct position.

A still further object of the invention is to provide an improved smoking pipe of the 45 above character which is efficient in use, one that is simple and easy to manufacture, and one which can be placed upon the market at a reasonable cost.

Other objects of the invention will appear 50 in the following detailed description, taken in connection with the drawings, forming a part of this specification, and in which drawings:

55 Figure 1 is a longitudinal section through the improved pipe showing the supplemental stem in elevation.

Fig. 2 is a similar view showing the supplemental stem in section.

Fig. 3 is a longitudinal section through the pipe with the bit removed and the supplemental stem partly withdrawn from the pipe bowl, and

Fig. 4 is a detail transverse section taken on the line 4—4 of Fig. 2.

Referring to the drawings, in detail, 65 wherein similar reference characters designate corresponding parts throughout the several views, the letter A indicates the improved pipe which includes the bowl B, the stem C, the bit D and the supplemental 70 stem E.

The pipe bowl B and the stem C may be of the ordinary or any preferred construction and may be formed of any desired material, such as hard wood, meerschaum, or the like, 75 and the stem C is provided with a relatively large longitudinally extending bore 5 for the reception of the supplemental stem E. The bore 5 of the stem C communicates with the bowl B and the lower end of the bowl is provided with an inwardly extending circular notch 6 which is in direct alinement with the bore 5 and is adapted to receive the inner end of the supplemental stem E when the same is placed in its operative position 85 in the stem B.

The supplemental stem E includes a cylindrical body 7, formed of hard wood or the like and is of sufficient size to snugly fit in the bore 5 of the stem and frictionally engage the wall thereof. The outer end of the cylindrical body 7 is provided with a screw threaded terminal 8 for the reception of the bit D which may be made of hard rubber, amber or the like, and the inner end 95 of the bit D is provided with a threaded socket 9 for the reception of the threaded extension 8 of the body 7. The bit D is provided with a longitudinally extending bore 10 which is in direct alinement with the longitudinally extending bore 11 formed in the cylindrical body 7, and the bores 10 and 11 form the passage-way for the smoke from the pipe bowl to the mouth of the user. The inner end of the cylindrical body 7 is provided with a relatively coarse external screw 100 thread 12, which provides a plurality of tortuous channels 13 and the lower face of the cylindrical body 7 at this point is provided with an inwardly extending longitudinal slot 14, with which the tortuous channels or passages 13 communicate.

105 110

The longitudinal slot 14 extends substantially half way through the cylindrical body 7 and terminates at the longitudinal axis of the same and communicates with the bore 11. The cylindrical body 7 is adapted to be positioned in the stem C in such a manner that the slot 14 will be at the lower end of the bore 5 of the stem and directly below the bowl B. This slot prevents water, saliva, moisture or the like, from entering into the pipe bowl, and forms a well for the collection of the same. Each of the passageways or channels 13 as stated communicates with the slot 14, and thereby provide a plurality of different openings for the entrance of smoke into the bore 11 and if any one of or a number of the passageways become clogged the smoke will still have an outlet or outlets through the bore. To prevent twisting or turning movement of the supplemental stem E in the stem C, a radially extending lug 15 is formed on the outer end of the supplemental stem and the lug is adapted to be received in a notch 16 formed in the outer face of the stem C. This lug 15 is placed diametrically opposite the slot 14 and forms means for permitting the smoker to exactly determine the position of the slot 14 in relation to the bowl B when the supplemental stem is placed in position, and it will be seen that when the lug 15 is placed in the notch 16 the slot will be in its correct position.

In operation of the improved smoking pipe A, the supplemental stem E is slid into the enlarged bore 5 of the stem C until its inner end engages in the pocket 6 and the lug 15 fits into the notch 16. The bit D is then threaded on the forward extension 8 into engagement with the outer face of the stem C. Upon the loading of the pipe and the lighting of the same, the smoke will circulate around the channels or the passageways 13 into the bores 11 and 10 and into the mouth of the user.

From the foregoing description it can be seen that an improved smoking pipe is provided in which the choking of the bore is absolutely prevented and which will maintain the tobacco in a dry condition.

Changes in details may be made without departing from the spirit or scope of my invention; but,

I claim:

1. The combination with a pipe including a bowl and a stem having a bore communicating with the lower end of the bowl, of a supplemental stem fitted in the first-named

stem and having a smoke passage formed therein, the inner end of the supplemental stem projecting into the lower end of the bowl and having an inwardly extending slot communicating with the smoke passage, and a plurality of spaced channels communicating with the slot.

2. The combination with a pipe including a bowl and a stem having a relatively large bore communicating with the lower end of the bowl, of a supplemental stem fitted in the bore and having a smoke passage, the inner end of the supplemental stem projecting into the bowl and having an inwardly extending slot communicating with the smoke passage, and a plurality of tortuous passages formed on the outer surface of the stem at the inner end thereof and communicating with the slot.

3. The combination with a pipe including a bowl and a stem having a bore communicating with the bowl, of a supplemental stem fitted in the bore and having a longitudinally extending passageway, the inner end of the supplemental stem projecting into the bowl, and external screw threads formed on the inner end of the supplemental stem, the supplemental stem having a longitudinally extending slot formed in its inner end communicating with the longitudinal passageway and with the screw threads, the slot being adapted to be positioned at the lower end of the bore in the bowl.

4. The combination with a pipe including a bowl, and a stem having a bore, of a supplemental stem fitted in the bore and having its inner end projected into the bowl, the inner end of the stem being provided with a relatively coarse external screw thread, and having an inwardly extending slot formed therein cutting the screw thread and communicating with the bore of the supplemental stem, a radially extending lug formed on the outer end of the supplemental stem, the outer surface of the first mentioned stem having a notch to receive said lug, said lug being positioned diametrically opposite the slot.

5. As a new article of manufacture, a supplemental stem for smoking pipes including a cylindrical body having a smoke passage extending longitudinally therethrough, one end of the stem having an external screw thread formed thereon, and an inwardly extending slot cutting the screw thread and communicating with the smoke passage.

WILLIAM EWART.
